UNITED STATES PATENT OFFICE.

DANIEL H. FITZGERALD, OF READING, PENNSYLVANIA.

REVERSIBLE LATCH.

SPECIFICATION forming part of Letters Patent No. 311,575, dated February 3, 1885.

Application filed August 20, 1884. (No model.)

To all whom it may concern:

Be it known that I, DANIEL H. FITZGERALD, of Reading, in the county of Berks and State of Pennsylvania, have invented a new and useful Improvement in Reversible Latches, of which the following is a specification.

My invention relates to latches which may be reversed in position to adapt them for a right or left hand door; and the essential object of the invention is to provide a means for reversing a latch-bolt, which is of such a simple nature and inexpensive construction that it may be embodied in the lowest-priced latches now made, as well as in the more expensive ones.

A further object of the invention is to provide a latch which can never be reversed unless the knob-spindle is removed, whereby all liability of the latch becoming reversed while in use is prevented. Ordinarily the spindle-hub whereby the latch is retracted is journaled in holes in the two plates of the lock-case, and is capable of a rotary motion only. In my improved latch the hub is made of a length to extend from the inner side of one plate to the inner side of the other plate, and is capable of sliding between the plates in a direction and to an extent sufficient to enable the reversible portion of the latch to be turned, and a spring is provided for returning the hub instantly after such sliding movement. The holes in the plates of the lock-case are only made large enough to receive the square knob-spindle, and to prevent the latch from being moved sufficiently to reverse the said latch-bolt. On the inner faces or sides of the plates of the lock-case are cast semicircular ribs or flanges, which form bearings for the hub and confine it against sliding movement in every direction save that necessary to permit the projection of the bolt sufficiently to allow of its being reversed.

The invention consists in novel combinations of parts hereinafter described, and pointed out in the claims.

In the accompanying drawings, Figure 1 is a view of a latch embodying my invention, one side plate of the case being removed. Fig. 2 is a sectional view on the dotted line $x-x$, Fig. 1. Fig. 3 is a sectional view of the hub and a portion of the case, the plane of the sectional view being on the dotted line $y-y$, Fig. 2.

Similar letters of reference designate corresponding parts in the several figures.

A A' designate two side plates of the lock-case, and A² is the face-plate thereof. B designates a portion of the latch-bolt, which consists of a yoke or fork guided between the projections $a a$ on the part A of the case, and also provided with upwardly-projecting ears or lugs b , on which the toes or ears c of the hub C act to withdraw the bolt in the usual way. The reversible portion B' of the bolt has at the inner end of its shank a head or flange, d , which is fitted to a cavity or socket, e , in the forked portion B of the bolt, so that the two parts B B' will move together longitudinally, while allowing of the part B' being turned independently of the part B, when withdrawn sufficiently to free the square nose of the latch-bolt from its slideway in the face-plate A². The part B' may be cast separately and its flange or head d dropped into a cavity or socket; or the shank and said head or flange may be covered with oil or parting-sand and placed in the mold of the part B before casting and the metal cast around it. As here shown the socket or cavity e is not entirely closed, but has an opening, e' , through which the parting-sand may be removed after casting. In this way provision is afforded for turning the reversible portion B' of the latch. The bolt B' has a shoulder, f , against which bears a spring, g , whereby the bolt is projected and the lugs or ears b held against the toes or ears c of the hub C. The hub C is shorter than those usually employed—that is, instead of its being long enough to project through and have journals in the plates A A' of the case, it is of such length that it may slide between the plates, as shown in Fig. 2. On the inner side of the plates A A' are cast lips or flanges h , which are semicircular in form, and which form journals for the hub. These lips or flanges confine the hub C against sliding in all directions save that in which it is necessary to project the bolt to reverse it, and the hub is held against movement, or has its movement in that direction resisted by a spring of any suitable form. I have here represented a straight steel spring, i , which is confined at its ends, and bears against a projection or toe, $*,$ on the hub, and thereby serves to hold the hub against movement toward the spring. The arrangement

of this spring is best seen in Fig. 3. The spindle F is square, and is fitted to the hub C, as is usual, and the holes j in the plates A A', through which the spindle is inserted, are of such size that the corners of the spindle fill them, and so prevent any sliding movement of the hub so long as the spindle is in place. The holes j in the plates of the case are not large enough to receive the hub C, and the ends of the hub therefore never enter these holes. Before the spindle has been placed in the hub, if it is desired to reverse the portion B' of the latch-bolt, it is only necessary to take hold of the nose of the bolt and pull it outward sufficiently to free its square portion from the hole in the face-plate. When the bolt is thus pulled out the spring i yields to the pressure of the hub C, and the two portions of the bolt and the hubs are all slid or pulled forward sufficiently to permit the turning of the bolt portion B' half round, whereupon the hub and bolt will be retracted or returned to normal position by the spring i acting on the hub. After the spindle is inserted the bolt cannot become reversed while in use.

25 A slight saving of metal is effected by making the hub of less length than usual, and this saving is almost sufficient to balance the cost of the spring.

30 My invention enables a reversible latch to be made at such slight expense that it may advantageously be embodied in the cheapest latches.

35 What I claim as my invention, and desire to secure by Letters Patent, is—

1. The combination, with the side plates, A A', of a lock-case, of the latch-bolt composed of the yoke or fork B, having ears b, and the part B', capable of being turned relatively to

the yoke B, a spring for projecting the bolt, 40 the hub C, consisting of a single piece of a length to fit and slide between the plates of the lock-case, and having toes e, which act upon the ears b to retract the bolt, and a spring for resisting the sliding movement of 45 the hub in a direction to project the bolt, substantially as herein described.

2. The combination, with the lock-case constructed with semicircular flanges h on their inner sides, of the hub fitting in said flanges 50 and capable of sliding between the plates of the case, a spring for resisting such sliding movement of the hub, and a latch-bolt comprising a reversible portion, substantially as herein described.

3. The combination, with a lock-case and a bolt comprising a reversible portion, of a hub arranged to slide between the plates of the case, a spring for resisting the sliding movement of the hub in a direction to project 60 the bolt, and a spindle fitting the hub, the plates of the lock-case being formed with holes which are of sufficient size to receive the spindle, but too small to receive the hub, and which prevent any sliding movement of the 65 hub so long as the spindle is in place, substantially as herein described.

4. The combination, with the plates A A', having semicircular flanges h, and the hub C, journaled therein and sliding between the 70 plates, of the spring i, extending across and bearing upon the hub, and confined at its ends, and the bolt B B', capable of operation by the hub, substantially as herein described.

DANIEL H. FITZGERALD.
